BEER CAN CLIP

Hermond G. Gentry, Atlanta, Ga., assignor to Atlanta
Paper Company, a corporation of Georgia

Application September 28, 1954, Serial No. 32,466

Term of patent 14 years

(Cl. D58—26)

Fig. 1

Fig. 2

Fig. 3

Fig. 1 is a side elevational view of a beer can clip showing my new design;

Fig. 2 is a bottom view thereof;

Fig. 3 is an end view thereof; and

Fig. 4 is a perspective view thereof.

The broken line showing of the beer cans in Fig. 4 are for illustrative purposes only.

I claim:

The ornamental design for a beer can clip, as shown and described.
